CLAIM

The ornamental design for a line roller for a spinning fishing reel, as shown and described.

DESCRIPTION

FIG. 1 is a front and left side of the perspective view of a line roller for a spinning fishing reel showing our new design; FIG. 2 is a front elevational view, the rear being a mirror image thereof;

FIG. 3 is a left side elevational view thereof;

FIG. 4 is a right side elevational view thereof;

FIG. 5 is a cross sectional view at No. 5 of FIG. 2;

FIG. 6 is a front and left side of the perspective view of the other embodiment showing our new design;

FIG. 7 is a front elevational view, the rear being a mirror image thereof;

FIG. 8 is a left side elevational view thereof;

FIG. 9 is a right side elevational view thereof; and,

FIG. 10 is a cross sectional view at No. 10 of FIG. 7.
